UNITED STATES PATENT OFFICE.

ANKER S. LYHNE, OF BRIDGEPORT, CONNECTICUT.

COMBINATION-CASE FOR FLASH-LIGHTS.

1,253,846.

Specification of Letters Patent. Patented Jan. 15, 1918.

Application filed October 19, 1915. Serial No. 56,737.

To all whom it may concern:

Be it known that I, ANKER S. LYHNE, a citizen of the United States, residing at Bridgeport, county of Fairfield, State of Connecticut, have invented an Improvement in Combination-Cases for Flash-Lights, of which the following is a specification.

This invention relates to what are known as "flashlights", devices so called comprising a conveniently shaped casing, generally of a size which permits the device to be carried in the pocket of a garment, provided with a small electric glow lamp with a reflector, containing one or more storage-battery cells with which said lamp is in circuit, and having a switch by means of which the current may be turned on and off. The standard casing is generally of tubular form, designed to receive and snugly contain two or more standard cylindrical cells in tandem arrangement, and the trade demands casings of different cell capacities. When the flashlight is intended for occasional and temporary uses, compactness is desired and a standard two-cell flashlight is demanded. When the lamp is to be used at frequent intervals or for a long continued period of time, a standard three-cell flashlight is called for. This has made it necessary for a dealer to carry an adequate stock of a plurality of sizes of casings.

The object of the present invention is the provision of a separately connected casing, one part containing the lamp and reflector and another the switch for making and breaking the circuit and a spring for holding the center contacts of the contained cells in engagement with each other and the lamp in circuit, and a casing-section of proper length adapted for interposition or substitution between said parts to increase the cell-capacity of the whole without the necessity of providing additional fastening means and without disturbing the functions of the lamp in one part and the switch and the spring in the other, whereby a dealer may readily make up from a relatively much smaller stock on hand standard or miner's two-cell or three-cell flashlights, or the user by a small additional outlay may become possessed of a lamp which may be in a moment transformed from a two-cell to a three-cell flashlight, or vice versa.

My invention will be more readily under-

stood by reference to the accompanying drawings, forming part of this specification, in which—

Figure 1 is a view partly in elevation and partly in section, showing a standard two-cell flashlight, comprising two members of my novel combination case;

Fig. 2 an elevation of a tubular member detached, which may be substituted for the shorter tubular member in Fig. 1 to make a standard three-cell flashlight case;

Fig. 3 a view partly in elevation and partly in section showing two members of my novel flashlight case assembled, said members comprising, when united with the body member (shown in Fig. 1) a miner's two-cell flashlight case, and

Fig. 4 is an elevation of a tubular member detached, which may be substituted for the shorter tubular member in Fig. 3 to make a miner's three-cell flashlight case.

My present invention is a development and carrying forward of the invention of Letters Patent 1,183,310 granted to me May 16, 1916.

11 denotes a standard body or main section which is used with all the several cases that may be made up from my novel combination case. This body is provided with a closed end, indicated by 12, a screw thread near its other end and above the thread a sleeve 13 which just fits within the several tubular members, past the screw threads thereon, so that in connecting the members of a sectional casing together, the sleeve of the body will first pass within the tubular member and serve as a guide to retain the two members in alinement, and when the threads engage, a complete connection of the members may be effected by rotating one or both of them without danger of an imperfect engagement and injury to the threads.

14 denotes a circuit-closer upon the outer side of the body, which may be of any ordinary or preferred construction, preferably the circuit-closer of my Patent No. 1,192,777, dated Dec. 29, 1914.

15 denotes a tubular extension member for use in a standard two-cell case (as in Fig. 1) and 16 a tubular extension member for use in a standard three-cell case. These members are provided at each end with a screw thread, the thread at one end being adapted to engage the body, and the thread at the other end to be en-

gaged by the lens-retaining ring 17. 18 denotes a lamp which is carried in the usual manner by a reflector 19, the edge of which is adapted to rest against the end of either 5 tubular member. 20 denotes the lens which rests upon the reflector, both lens and reflector being retained in place by ring 17, which has a flange adapted to grip the edge of the lens. 21 denotes a battery cell having 10 a center contact adapted to engage the center contact of a lamp in the usual manner. These contacts are held in engagement by means of a spring 22 in the body, upon which the inner battery cell rests. 15 As already stated, Fig. 1 shows a standard two-cell flashlight. If a standard three-cell flashlight is required, tubular extension member 15 is detached from the body, the lens and reflector removed therefrom, and 20 attached to tubular extension member 16, and the latter attached to the body. The ability to make this change is often quite important, as, for temporary use, the operator desires to have the lamp as compact as 25 possible, while for long-continued use he requires the additional battery power. The change is easily and quickly made and in either form the lamp is convenient for use, as the circuit-closer is conveniently placed 30 on the body member which is common to all the forms.

23 denotes a tubular extension member for use with a miner's two-cell case (as in Fig. 3) and 24 a tubular extension member for 35 use with a miner's three-cell case. These extension members are provided at each end with a screw thread, the thread at one end being adapted to engage the body and the thread at the other end to be engaged by the 40 head 25 of a miner's flashlight. It is sufficient for the purposes of this specification to state that in miners' flashlights, as ordinarily constructed, the reflector, carrying the lamp, and the lens are secured to the 45 head by a retaining ring 26 and that the head is adapted to engage either tubular extension member in the same manner that the lens-retaining ring does in the standard type of flashlights. To make a miner's two-cell 50 flashlight case, the head is attached to tubular member 23, as in Fig. 3, and said tubular member is attached to the body. To make a miner's three-cell flashlight case, the head is attached to tubular extension member 24 55 and then said member is attached to the body. By providing tubular extension members 23 and 24 in addition to tubular mem-

bers 15 and 16, I am enabled to use standard batteries in both types of flashlights.

Having thus described my invention, I claim:—

1. An improved flashlight comprising a casing formed of a main section and a detachable extension section, the main section being closed at one end, a lamp, means detachably engaging the extension section for retaining said lamp in position, a source of electrical energy within the casing and in circuit with the lamp, a contact device between the closed end of the main section and 65 the source of energy, and a switch carried by the main section and controlling the circuit to the lamp, said main section and said extension section being detachably connected, whereby extension sections of different lengths may be interchangeably employed and the switch and contact device carried by the main section will be undisturbed. 70

2. An improved flash light comprising a 80 casing formed of a main section and a plurality of superposed extension sections detachably connected, the main section being closed at one end, a lamp, means detachably engaging one of the extension sections for 85 retaining said lamp in position, a source of electric energy within the sections and in circuit with the lamp, a contact device between the closed end of the main section and the source of energy, and a switch carried 90 by the main section and controlling the circuit to the lamp, said main section and said extension section being detachably connected, whereby extension sections of different lengths may be interchangeably employed and the switch and contact device 95 carried by the main section will be undisturbed. 100

3. An improved flashlight comprising a tubular body closed at one end, an extension member having one end detachably engaging the other end of said body, whereby extension members of different lengths may be interchangeably employed, a retaining ring removably engaging the free end of the extension member, one or more batteries within the body and the extension member, the number of batteries being variable in accordance with the length of the extension member, a lamp maintained in circuit with 110 the batteries by said retaining ring, and a circuit closer carried by said body. 105

In testimony whereof I affix my signature.
ANKER S. LYHNE.
